CONTROL SYSTEM

Wade H. Wineman, Michigan City, Ind., assignor
to Sullivan Machinery Company, a corporation
of Massachusetts

Application June 28, 1940, Serial No. 343,008

8 Claims. (Cl. 121—158)

This invention relates to control systems for motors, and more particularly to apparatus for automatically controlling the supply to and exhaust from motor cylinders, such as pumping motor cylinders, of operating pressure fluid.

In oil wells in which the bottom hole pressure has become so reduced that the oil ceases to flow naturally from the wells, it has become common practice to produce each well by a pump located near the bottom of the well, and to drive the pump by a rod connected to a power-driven reciprocating device located at the top of the well. Such reciprocating devices are of various types, and one very satisfactory arrangement utilizes a piston operating in a cylinder which is arranged with its axis in vertical alinement with the axis of the well and to which cylinder operating pressure fluid is supplied, beneath the piston therein, to move the piston on its working stroke, and from which cylinder the pressure fluid is exhausted against a back pressure to control the downward stroke of the piston and its supported load. Motors used for such purposes heretofore have in most instances, it is believed, had individual distributing valves for controlling the supply and exhaust of pressure fluid with respect to their motor cylinders, and such valves have been operated either by mechanical means or by pressures which control the movements of the motor pistons. By connecting a number of motor cylinders to a single pipe line and providing a single distributing valve for connecting this line either to a source of fluid under pressure sufficient to raise the motor pistons or to an exhaust under pressure sufficient to control the downward strokes of the pistons, there may be provided a much simpler and less expensive system. Such a system may be designed to connect a line leading to one group of motor cylinders to a source of operating pressure and at the same time to connect a line leading to a second group of motor cylinders to exhaust, and the valve may be operated by pressures built up in the fluid-supplying line after the pistons in the cylinders connected to that line have all reached the tops of their working strokes, to connect such line to exhaust pressure and to connect the line to the second group of cylinders to the source of operating pressure. And by maintaining the return line under a back pressure, the lowering of the pistons during the suction strokes of the pumps may be controlled.

It is evident that the loads on the various motor pistons will vary according to the depths at which the pumps are located, the friction be-

tween the working parts and various other operating conditions. If pressure fluid is supplied through a line to several motor cylinders beneath pistons carrying different loads without control, the pistons lifting the lighter loads will reach the tops of their working strokes first and the bottoms of their downward strokes last. Since it is desirable that the pumps be operated without appreciable pauses of their pistons at the ends of their strokes, it will be desirable to provide for each motor cylinder a manually adjustable means for automatically controlling the rates of supply to and exhaust from the motor cylinders, of pressure fluid.

15 It is an object of this invention to provide an improved control system for expansible chamber motors. It is another object of this invention to provide improved means for controlling the supply and exhaust of pressure fluid relative to the 20 cylinders of the expansible chamber motors. It is still another object of this invention to provide an improved distributing valve for a control system for expansible chamber motors. Still another object of this invention is to provide an 25 improved distributing valve for connecting one line to supply pressure and another line to exhaust pressure and having associated therewith means operative at predetermined pressures in the supply-effecting line for reversing the connections to said lines. Yet another object of the 30 invention is to provide an improved pumping system. Still a further object is to provide for improved means for controlling the lowering of pump motor pistons while conserving energy 35 during the working strokes. Other objects are to provide improved means for regulating the rates of travel of the pump motor pistons, for taking care of leakage, for preventing overspeeding, for providing cushioning without sacrifice of power, for automatically checking undesirable increases in speed of working strokes, and for automatically regulating down strokes. These 40 and other objects of the invention will herein-after more fully appear.

45 In the accompanying drawings, in which there are shown for purposes of illustration several forms which the invention may assume in practice,

50 Fig. 1 is a diagrammatic view in plan showing one illustrative form of the improved pumping system.

55 Fig. 2 is an enlarged developed vertical sectional view of the pressure operated fluid distributing valve and control means therefor, taken substantially on planes of line 2—2 of Fig. 1.

Fig. 3 is a sectional view similar to Fig. 2, showing the valve in a different position, and showing only part of the valve control means.

Fig. 4 is a top end view of one pump motor unit.

Fig. 5 is a vertical sectional view through the pump motor unit shown in Fig. 4, taken substantially on line 5—5 of Fig. 4.

Fig. 6 is an enlarged vertical sectional view taken substantially on line 6—6 of Fig. 5 and 10 showing valves for controlling the flow of pressure fluid to and from the pump motor cylinder.

Fig. 7 is a vertical sectional view showing two pump motors of modified form, with their associated pistons at different points in their working strokes.

Fig. 8 is an enlarged cross sectional view on line 8—8 of Fig. 7, taken through one of the pump motors of Fig. 7.

Fig. 9 is a vertical sectional view on line 9—9 of Fig. 8, showing valve mechanism for controlling flow of pressure fluid to the motor cylinder.

Fig. 10 is a vertical sectional view on line 10—10 of Fig. 8, showing valve mechanism for controlling discharge of pressure fluid from the motor cylinder.

Fig. 11 is a diagrammatic view in plan, showing a modified form of the improved pumping system.

Fig. 12 is a diagrammatic view in plan, showing another form of the improved pumping system.

In the illustrative form of the invention shown diagrammatically in Fig. 1, a fluid pump 1 is connected to a motor 2 through transmission mechanism 3 and is driven by the motor to pump fluid from a storage tank 4 to the cylinders of either a bank A or a bank B of motors for operating pumps in oil wells. The fluid is pumped from the tank 4 through a connection 5, and the pump 1 discharges it through a connection 6 to a fluid distributing valve mechanism generally designated 7. In one limit position of the distributing valve, fluid is delivered from the connection 6 to a connection 8 leading to the cylinders of the motors in bank A and at the same time fluid is discharged from cylinders of the motors in bank B through a pipe connection 9 to the fluid distributing valve and through the valve to a connection 10 leading to the storage tank 4. In another limit position of the distributing valve, the connection 9 leading to the motor cylinders of bank B is connected to the supply line 6, and the connection 8 leading to the cylinders of bank A is connected to the connection 10 opening back into the storage tank. The pressure of the fluid delivered by the pump is sufficient to raise the pistons in the cylinders of the motors to which it is supplied, and the fluid in the storage tank is maintained under a pressure by means which will be shortly described, to prevent the pistons in the motor cylinders connected to discharge from descending too rapidly.

When all the pistons in the motor cylinders connected at one time to the supply line reach the tops of their strokes, there will be built up in the line 8 or 9, whichever is acting as the supply line, a pressure which will operate means that will shortly be described to supply fluid to move the distributing valve into a position to connect the other group of cylinders to supply and to connect the first mentioned cylinders to the storage tank. The small quantities of fluid used in reversing the distributing valve are discharged, as will later be explained in more detail, through

a connection 11 to a make-up tank 12. A make-up pump 13 is driven by the motor 2 to pump fluid drawn from the make-up tank through a connection 14, by way of a connection 15 into the storage tank 4 at a rate sufficient to maintain the pressure in the tank at the desired value. It will be appreciated that starting with the tank 4 filled with air, the pumping of oil or other hydraulic fluid into it by the make-up pump will build up a pneumatic pressure in the upper part of the tank which will provide a back pressure on the return line 10 and furnish a cushion. Any suitable means, not shown, may be used to introduce more air, if necessary, into the tank 4.

Referring now to Figs. 2 and 3, it will be noted that the distributing valve mechanism 7 comprises a body portion 18 having a plane upper surface 19 upon which there is mounted a cylinder block 20 having aligned bores 21 parallel to the surface 19. Reciprocably mounted in the bores 21 are pistons 23 and 24 connected by a reduced portion 25. An opening 26 through the wall of the block 20 connects the space between the ends of the bores 21 with the plane upper surface of the body portion and forms with the space between the bores 21 a chamber or valve chest in which a D valve can move. Formed in the reduced portion 25 connecting the pistons 23 and 24 is an opening 28 which receives a projecting portion 29 formed on a D slide valve 30, and the valve 30 moves within the opening 26 in the cylinder block in sliding engagement with the plane surface 19. Formed in the body portion 18 are passages 32, 33 and 34 opening through the plane surface 19 into the valve chest. The passages are so arranged that in one limit position of the valve 30 a groove 35 formed in the valve connects passages 32 and 34 and in another limit position of the valve the groove 35 connects passages 33 and 34. Passage 34 is connected by pipe 10 to the tank 4. Pipe 8 is connected to passage 32, and pipe 9 connects with passage 33. The supply connection 6 leading from the fluid pump discharge is connected, through an opening in the upper wall of the cylinder block 20, in communication with the space between the bores 21, 21 and with the chamber 26.

The body portion 18 is herein shown as having a pair of upwardly projecting bosses or portions 38 and 38' upon its upper side. As shown in Fig. 1, these are laterally off-set from the axial line of the member 20, but in Figs. 2 and 3 they are shown, in these "developed" views, as though they overlie the passages 32 and 33. Details of construction associated with the projection 38 will be described, and it will be appreciated that similar structure is associated with the projection 38'. Within the projection 38 is formed a chamber 39 opening through the top of the projection 38, and through a reduced opening 40 opening directly into communication with (or, see Fig. 1, into communication through a branch passage with) the passage 32. The opening 40 has therein a plug 41 which is threaded into the opening 40 and is provided with stepped bores 42 and 43 serving to connect chamber 39, as shown in Figs. 2 and 3, with passage 32. A valve seat 44 is provided at the junction of bores 42 and 43. Threaded into the upper end of boss 38 and forming a closure for the top of the chamber 39 is a member 45 having an opening 46 for guiding a valve stem 48 which has an enlarged valve 50 formed on its lower end for engaging the valve seat 44. Resting upon

the valve 50 is an annular valve plate 52 having an outer diameter slightly less than the diameter of the bore 42 and desirably received, at least in part, within the bore 42 when the valve 50 is seated. A member 54 having a bore 55 of the same diameter as the bore 42 is threaded within the chamber 39 so that its lower end is slightly above the upper end of the member 41 and so that the bores 42 and 55 are in axial alignment. Resting upon the plate 52 and surrounding the valve stem is a coil spring 57 which engages the lower surface of the member 45 and urges the valve 50 into engagement with the valve seat 44. Extending from the lower end of the valve 50 through the bore 43 are guides 58 cooperating with the walls of the bore to guide the valve relative to the valve seat. A cap 59 threaded on the member 45 engages the top of the projecting portion 38 and locks the member 45 in its adjusted position. A chamber 61 surrounding the upper portion of the valve seat member 41 communicates with the bores 42 and 55 through the space between the members 41 and 54 and is connected by a passage 62, a pipe connection 63 and a passage 64 formed in a cylinder head 65, which closes the outer end of the right-hand bore 21 of Fig. 2, with the end of the cylinder bore 21 adjacent piston 24. A pipe connection 67 connects the chamber 39 to the pipe connection 11 leading to the make-up tank 12. The projecting portion 38 formed on the body portion 18 at a point opposite the portion 38 is, as previously noted, similar to the projecting portion 38, and this portion 38' contains a chamber 39' which is closed at its upper end by a member 45' threaded into the chamber and locked in position by a cap 59'. A valve stem 48' is guided in an opening 46' in the member 45' and carries at its lower end a valve 50' for engaging a valve seat 44' formed on a member 41'. An annular plate 52' is supported on the valve and is movable within bores 42' and 55' formed in members 41' and 54' respectively. A spring 57' is compressed between the plate 52' and the bottom surface of the member 45' and urges the valve 50' towards the valve seat 44'. A chamber 61' surrounding the upper portion of the member 41' communicates with bores 42' and 55' and is connected through a passage 70, a pipe connection 71 and a passage 72 in the cylinder block 20 with the outer end of the bore 21 which contains the piston 23. A pipe 74 connects the chamber 39' with the pipe 11 leading to the make-up tank 12.

The operation of the distributing valve will be clearly apparent from the description given. Assuming that the parts are in the positions shown in Fig. 2, fluid will be delivered from the pump 1 through pipe connection 6 to the valve chest in the cylinder block 20, where it will flow around the reduced portion 25 and then through passage 32 and the pipe connection 8, to the cylinders of the motors in bank A. At the same time fluid will be discharged from the cylinders of the motors in bank B through pipe connection 9, passage 33, the groove 35 in valve 30, passage 34 and pipe 49, to the storage tank 4. When the pistons in the cylinders of the motors in bank A all reach the tops of their strokes and there is no further increase in the space receiving pumped fluid, a pressure will be built up in the passage 32 sufficient to raise valve 50 from its seat against the force of spring 57. As the valve moves from its seat, pressure fluid flows through the bore 43, past the valve seat and against the lower surface

of the plate 52. The action of the pressure fluid against the increased surface area effects rapid movement of the valve to its full open position, so that the plate 52 enters the bore 55 to obstruct the flow of fluid into chamber 39 and to direct flow through the space between members 41 and 54 to the chamber 61, where it enters the passage 62 and is conducted to the bore 21 through pipe connection 63 and passage 64. The pressure fluid entering bore 21 acts upon the end of piston 24 to throw it to the left, causing piston 23 to force any fluid in the left end of bore 21 through passage 72, pipe connection 71 and passage 70, to the chamber 61', which, as previously noted, is vented freely to the make-up tank 12 when plate 52' is in its lower position. Since the pressure in passage 33 will only be equal to exhaust line pressure and insufficient to raise valve 50' from its seat, plate 52' will be in its lower position, and the chamber 61' will be freely connected through the space between members 41' and 54' to the chamber 39' through bore 55', and fluid displaced into chamber 39' will be conducted through pipe 74 and pipe 11 to the make-up tank 12. As the pistons 23 and 24 move to the left, the valve 30 is moved with them, and when piston 23 engages the left end of bore 21 the valve will be in a position to connect passages 32 and 34 through groove 35. Pressure fluid will then be supplied from pump 1 through connection 6 to passage 33, and through pipe 9 to the cylinders of the motors in bank B, and move the pistons in the cylinders of those motors upwardly. The loads carried by the pistons in the motors of bank A will cause them to force fluid from the cylinders through pipe connection 8, passage 32, groove 35, passage 34 and pipe 10, to the storage tank 4 against the pressure that is maintained therein to control the rate of discharge. It will of course be understood that the springs 57 and 57' will have been compressed by adjustment of members 45 and 45' to permit opening of valves 50 and 50' only when the valves are subjected to a pressure exceeding that necessary to raise the pistons in the motor cylinders. With the pistons in the motors of bank A moving downwardly against the pressure in the storage tank, the pressure in the passage 32 will be such that the valve 50 will be held in its closed position. (In Fig. 2, since passage 33 is connected to exhaust and passage 32 is presumed to be still conducting pressure fluid to raise the pistons in the cylinders of bank A, the valves 50 and 50' are both shown seated.) Returning to the point in the cycle that was being described prior to the parenthesis, it will be understood that when the pistons in the cylinders supplied by pipe 9 all reach the upper ends of their strokes, a pressure will be built up in passage 33 which will open valve 50' and pressure fluid will flow past the valve seat 44' to chamber 61' and through passage 70, pipe 71 and passage 72 into the end of the cylinder bore 21 adjacent piston 23. The pressure fluid will throw pistons 23 and 24 to the right, forcing any fluid in the end of the bore adjacent piston 24 through passage 64, pipe 63, passage 62, bore 55, chamber 39 and pipes 67 and 11 to the make-up tank 12. The above cycle of operation will be repeated on continued supply of pressure fluid from pump 1.

Figs. 4, 5 and 6 show one of the motors of banks A and B of Fig. 1 and an improved valve means for controlling the rate of fluid flow to and from the motor cylinder. This motor, generally designated 76, comprises a cylinder 77 hav-

ing a bore 78 which is closed at its upper and lower ends respectively by cylinder heads 79 and 80. Reciprocable in the bore 78 is a piston 82 having a piston rod 83 extending through packings 84 and 85 in the lower cylinder head and connected to a pump rod 86. Threaded in an opening 87 in the cylinder head 79 is a threaded rod 89 having a spring 90 attached to its lower end in axial alinement with the cylinder bore. This spring is quite powerful and is adapted to bring the relatively slowly upwardly moving piston to rest without substantial shock.

Arranged in the lower cylinder head 80 is a valve mechanism, generally designated 92, having a lower chamber 93 with which a pipe 94 is connected. The pipe 94 is connected to one of the lines controlled by the distributing valve mechanism 7. An upper chamber 95 in the valve mechanism 92 is connected with the chamber 93 through a circular opening 96 in a vertically extending portion of the wall separating the two chambers. Members 97 and 98 threaded into openings in the side walls of chambers 95 and 93 support adjustable rods 99 and 100 in alinement with the horizontal axis of opening 96. A valve member 101 loosely fitting opening 96 is provided with extending portions 102 and 103 having bores 104 and 105 for receiving the rods 99 and 100 respectively. The chamber 95 is connected through an opening 107 at its upper end to a passage 108 leading to the lower end of a bore 109 formed in the lower cylinder head and opening into the lower end of the cylinder bore 78. The bore 109 is somewhat less in diameter than the cylinder bore and receives, when the motor piston moves to its lower position, a projecting portion 110 formed on the piston. A passage 111 in the lower cylinder head connects the passage 109 to a recess 112 opening into the lower end of the cylinder bore 78, and a ball valve 114 seating upon a surface surrounding the upper end of passage 111 prevents fluid discharge from the cylinder bore but permits fluid flow through passage 111 toward the cylinder bore. Valve means are provided for controlling fluid flow through opening 107, and this means comprises a valve member 116 loosely fitting opening 107 when in raised position and having a lower valve stem 117 with a reduced end portion 118 fitting into an opening through a projecting portion 119, and an upper valve stem 120 extending into an opening 121 in a plug 122 threaded into the upper end of a chamber 123, which is above and alined with the axis of the opening 107. A spring 124 in the opening 121 acts against the upper end of valve stem 120 and is kept under compression by an adjustable plug 125, and presses the valve member 116 towards its lower position. A plug 125' closes the opening 121 at its upper end. A larger spring 126 is compressed between the lower surface of plug 122 and a plate 127 resting upon a projecting wall portion 128 surrounding an opening 129 which connects chamber 123 with the passages below it. A collar 130 formed on the valve stem 120 engages the lower surface of plate 127 when the valve member 116 is moved upwardly into the opening 107, and may unseat the plate 127.

Operating liquid passing the piston 82, when any substantial quantity accumulates, will flow into a recess 132 formed in a plug 133 threaded into an opening in the upper surface of the piston. A rod 134 passes through an opening in the plug 133 and has attached to its upper end a plate 136 which engages the lower end of spring

90 as the motor piston approaches the upper end of its stroke. On continued upward movement of the motor piston, a plunger 137 formed on the rod 134 is pressed into the recess 132, forcing any liquid in the recess through a passage 138, past a spring pressed ball valve 139 and through a passage 140 into the cylinder bore beneath the motor piston.

The operation of this motor is as follows: Assuming that the motor piston is resting against the lower cylinder head 80 and that fluid is supplied through pipe 94 to chamber 93, from which it flows through opening 96 to chamber 95 and then passes through opening 107 and passage 108 to the cylinder bore beneath the motor piston, it will move the piston upwardly in the cylinder bore if the fluid is delivered at a sufficiently high pressure. Fluid flowing through opening 96 will act against the valve 101, moving it to its left-hand position shown in Fig. 6, where it offers but little resistance to the flow of fluid. Valve member 116 is held in its lower position by spring 124 and permits the desired rate of fluid flow through opening 107. If the motor piston is moved upwardly too fast, for any reason, the high rate of fluid flow around the valve member 116 will move it toward or into the opening 107, reducing or nearly occluding the flow opening and cutting down the supply to the cylinder bore. The pressure fluid passes from the cylinder bore through passage 140 in the motor piston, to the space beneath the plug 133, and acts on the lower end of rod 134 to move it with the plate 136 and the plunger 137 into a raised position. When the plate is moved into engagement with spring 90, the plunger 137 is pressed into recess 132, forcing any fluid therein back into the lower portion of the cylinder bore, and the upward movement of the piston is stopped. If the pipe 94 is then connected to exhaust, the motor piston will be moved downwardly by its supported load and fluid will be forced from the cylinder through passage 108, past valves 116 and 101, to pipe 94. The valve 116 will be moved to its full open position by the spring 124 and the flowing fluid, but valve 101 will be moved to the right by the fluid until it engages the end of rod 100 and then held in a position to permit only the desired rate of discharge. As the projecting portion 110 on the lower surface of the motor piston enters the reduced bore 109, fluid will be entrapped between the surface on the head surrounding the bore 109 and the piston to prevent contact between the piston and cylinder head.

In Fig. 7 there are illustrated two motors, generally designated 145 and 146, similar to that of Fig. 5 except that they are each provided with a modified form of valve means for controlling the flow of pressure fluid and have some of the refinements of the motor of Figs. 4 to 6 omitted. Since the two motors of Fig. 7 are identical in construction, only motor 145 will be described, and primed numbers will be given to corresponding parts of motor 146 to aid in describing its operation. Motor 145 comprises a cylinder 147 having a bore 148 closed at its upper and lower ends by heads 149 and 150 which are secured to the cylinder by rods 151. The motor is supported by legs 152 in a vertical position so that a piston rod 153 connected to a piston 154 reciprocable in the cylinder bore extends through the lower cylinder head and connects to a pump rod 155. A rod 157 is threaded through an opening 158 in the upper cylinder head and has attached to its lower end a spring 159 extending axially of the

cylinder bore. A combined supply and exhaust pipe line 160 is connected through branching connections 162 and 163 to passages 164 and 165 formed in the lower cylinder head and opening into the lower end of the cylinder bore. In the branch connection 162 is a ball valve 166 seating on a surface surrounding an opening 167 for preventing fluid flow from the cylinder bore toward pipe line 160, but this ball valve is movable from its seat to permit flow of fluid from pipe 160 toward the cylinder bore. A manually controlled stop valve 168 in the branch connection 162 may be adjusted to stop all flow through the branch or to limit the flow to any desired rate. A ball valve 170 in the branch connection 163 permits fluid flow from the cylinder bore to the pipe line 160 but prevents flow in the opposite direction, and a stop valve 171 may be manually adjusted to stop or limit the flow through the same branch.

Assuming that the motor pistons are in their lower positions and that fluid is supplied to pipe line 160 at a pressure sufficient to raise the pistons in the bores of the cylinders, there will be a flow of fluid through the branch connections 162 and 162' to the cylinder bores beneath the pistons, and the pistons will be moved upwardly. The rate of flow through the branch connections will be controlled by the adjustment of the throttle valves 168 and 168'. When the motor pistons approach the upper limits of their strokes, they engage the springs 159 and 159' and are brought to a stop. If one of the pistons reaches the upper end of its stroke before the other piston, as shown in Fig. 7, it will be held in that position by the pressure fluid until the other motor piston reaches the upper end of its stroke, and then, since there will be no substantial further increase in the volume of the space connected to the supply line, a pressure will be built up in the line to operate a distributing valve, such as that shown in Figs. 2 and 3, and bring about a connection of the line to exhaust. The motor pistons will then be moved toward the lower ends of the cylinders by their own weight and the weight of the parts connected to them, and fluid within the cylinder bores will be forced through the branch connections 163 and 163' at rates depending on the adjustments of the manually controlled valves 171 and 171'.

In Fig. 11 there is shown an internal combustion engine 175 driving a main line pump 176 and a make-up pump 177 through a belt connection 178. The pump 176 takes fluid from a storage tank 179 through a pipe connection 180 and delivers it through a pipe 181 to a distributing valve 182, where it is conducted either to a pipe connection 183 leading to motors in a bank C or to a pipe connection 184 leading to motors in a bank D. While fluid is being supplied to one of the pipe connections, the other pipe connection is connected through the distributing valve to a pipe connection 185 leading to the storage tank. The distributing valve is of the same construction as that shown in Figs. 2 and 3, and fluid used in reversing the valve is returned through pipes 187 or 188 to a make-up tank 189 or is pumped by the make-up pump 177 through a pipe connection 190 to the storage tank, depending on the position of a selector valve 191.

Fig. 12 shows a system in which an electric motor 192 is directly connected through a shaft 193 to a main line pump 194 and a make-up pump 195. The pump 194 takes fluid from a storage tank 196 through a pipe line 197 and delivers it to a distributing valve 198 through a pipe connec-

tion 199. The valve 198 distributes the fluid either to a pipe line 200 leading to a motor bank E or through a pipe line 201 to a motor bank F. While fluid is supplied to a pipe line leading to one of the motor banks, it is discharged from the other through the distributing valve to a pipe 202 leading to the storage tank. Fluid taken from the supply line for reversing the distributing valve is discharged through a pipe 203 to a make-up tank 204 from which it is pumped by the make-up pump to the storage tank through a pipe 205.

As a result of this invention, it will be noted that improved systems for controlling the supply and exhaust of pressure fluid relative to pump operating motors have been provided. Associated with the control systems is an improved distributing valve and improved valve means for controlling the flow of pressure fluid relative to each motor. The systems are not only very economical due to the use of single pipe lines each of which acts as both a supply and a discharge line for a group of motors, but also due to the control of supply and discharge relative to each line by one distributing valve, which makes it possible to locate this valve with the motors and pumps where it can be cared for by a single attendant. It will be observed that improved means for preventing overspeeding of the motor pistons in either direction, and improved means for independently controlling the rates of opposite piston movements, are provided. Improved means for precluding stalling on starting, and improved means for caring for leakage, are provided. And improved means for preventing damage through shocks and for delaying distributing-valve shifting until each of the pistons to which it supplies fluid has normally completed its stroke, are provided.

While there are in this application specifically described several forms which the invention may assume in practice, it will be understood that these forms of the same are shown for purposes of illustration, and that the invention may be further modified and embodied in various other forms without departing from its spirit or the scope of the appended claims.

What I claim as new and desire to secure by Letters Patent is:

1. In an apparatus of the character described, a pressure fluid actuated distributing valve, and controlling means for said valve including a pilot valve subjected to the pressure distributed by said distributing valve and controlling a throwing connection for said distributing valve, said pilot valve having means moving therewith on opening thereof to increase its rate of opening movement, and means for venting the throwing fluid which passes said valve and with which increased flow area is provided on closing of said valve.

2. In a valve mechanism, in combination, a fluid actuated distributing valve and means for controlling the flow of actuating fluid relative to said distributing valve including a valve-seat-providing member, a valve adapted to seat on said member, an annular passage surrounding said member and communicating with said distributing valve, a member coaxial with said first mentioned member and spaced therefrom to provide an annular slit communicating with said annular passage, a disc movable with said valve and when said valve is closed disposed mostly below said annular slit and when said valve is open disposed above said annular slit, said second mentioned

member having a circular opening therethrough providing a limited clearance around the periphery of said disc when said valve is open, and means for venting fluid passing through said opening.

3. In a valve mechanism, in combination, a distributing valve, fluid actuated means for controlling said distributing valve, passage means communicating with said fluid actuated means, a fluid supply connection, a fluid vent connection, and means including a valve member subjected to the pressures of the fluid distributed by said distributing valve for controlling the connection of said passage means to said supply connection and to said vent connection, said valve member operative at one predetermined pressure of the fluid for connecting said passage means to said supply connection and operative at a different predetermined pressure for connecting said passage means to said vent connection.

4. In a valve mechanism, in combination, a distributing valve, fluid actuated means for controlling said distributing valve, passage means communicating with said fluid actuated means, a fluid supply connection, a fluid vent connection, and means for controlling the connection of said passage means to said supply connection and to said vent connection, said last mentioned means including fluid actuated valve means subjected to the pressures distributed by said distributing valve, said valve means normally connecting said passage means to said vent connection and operating at a predetermined maximum pressure for connecting said passage means to said supply connection.

5. In a valve mechanism, in combination, a distributing valve, fluid actuated means for controlling said distributing valve, passage means communicating with said fluid actuated means, a vent connection, a fluid supply connection leading from said distributing valve, and means including a pilot valve subjected to the pressures in said fluid supply connection and operative at predetermined pressures for connecting said passage means directly to said vent connection or to said fluid supply connection, said pilot valve operating at a maximum pressure to connect said passage means to said supply connection.

6. In a valve mechanism, in combination, a distributing valve, fluid actuated means for controlling said distributing valve, and means for controlling the flow of actuating fluid to and from said fluid actuated means including a valve seat,

a valve engageable with said seat and subjected continuously to the pressures of the fluid distributed by said distributing valve, a passage extending axially from said valve seat, passage means communicating with said passage between the ends of the latter for conducting operating fluid to and from said fluid actuated means, means for venting fluid from the end of said passage remote from said valve seat, and means movable with said valve between points at the opposite sides of the point of communication of said passage means with said passage for connecting said passage means successively in communication with said valve seat and said venting means.

7. In a valve mechanism, in combination, a distributing valve, fluid supply and exhaust connections, passage means adapted to be connected by said distributing valve to said fluid supply and exhaust connections, fluid actuated means for controlling said distributing valve, said fluid actuated means operative on the supply of pressure fluid thereto for actuating said distributing valve to connect said passage means to said exhaust connection, a throwing connection for said fluid actuated means, venting means, and means including a pilot valve subjected to the pressures in said passage means for controlling the connection of said throwing connection with said venting means and said passage means.

8. In a valve mechanism, in combination, a distributing valve, fluid supply and exhaust connections, passage means adapted to be connected by said distributing valve to said fluid supply and exhaust connections, fluid actuated means for controlling said distributing valve, said fluid actuated means operative on the supply of pressure fluid thereto for actuating said distributing valve to connect said passage means to said exhaust connection, a throwing connection for said fluid actuated means, venting means, and means including a pilot valve subjected to the pressures in said passage means for controlling the connection of said throwing connection with said venting means and said passage means, said pilot valve operative at a predetermined maximum pressure in said passage means for connecting said throwing connection in communication with said passage means, and operative when said passage means is connected to exhaust for connecting said throwing connection in free communication with said venting means.

WADE H. WINEMAN.
